Primary Examiner — Steven J Czyz*(74) Attorney, Agent, or Firm* — Sterne, Kessler,
Goldstein & Fox P.L.L.C.(57) **CLAIM**

The ornamental design for a display with stand, as shown and described.

DESCRIPTION

FIG. 1 is a top front perspective view of a display with stand showing the claimed design;

FIG. 2 is a top rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show environment and portions of the display with stand that form no part of the claimed design.

1 Claim, 7 Drawing Sheets
